UNITED STATES PATENT OFFICE.

WILLIAM J. CUSSEN, OF RICHMOND, VIRGINIA, ASSIGNOR OF TWO-THIRDS
TO M. MILLHISER & CO., OF SAME PLACE.

TOBACCO-BAG.

SPECIFICATION forming part of Letters Patent No. 355,640, dated January 4, 1887.

Application filed September 10, 1886. Serial No. 213,214. (Model.)

To all whom it may concern:

Be it known that I, WILLIAM J. CUSSEN, a citizen of the United States, residing at Richmond, in the county of Henrico and State of Virginia, have invented certain new and useful Improvements in Tobacco-Bags, of which the following is a specification, reference being had therein to the accompanying drawings.

This invention relates to certain improvements in bags for tobacco, which in prime condition necessarily contains a certain amount of moisture; and it has for its object to provide for packing the tobacco in an original package from which portions may be taken from time to time, the bag being of such nature as to preserve the tobacco in its original condition by retaining the moisture until it is exhausted.

The invention further has for its object to provide a bag which will be sufficiently ornamental to serve as a pouch for carrying the tobacco about the person, and which may, by means of a string concealed in a flap or pocket which seals the mouth of the bag primarily, be secured around the tobacco as it is diminished by use, so as to preserve the tobacco always in prime condition. These objects I attain by the means illustrated in the accompanying drawings, in which—

Fig. 1 represents a perspective view of a bag packed and forming an original package. Fig. 2 represents a similar view of the bag after it has been opened, showing the means for securing it to prevent evaporation. Fig. 3 represents a view showing the flap or pocket carrying the concealed string, with the string partially drawn out; and Fig. 4, a modification of my invention in which a hook is employed in connection with the flap in place of the string to secure the bag after it has been opened.

The letter A indicates a bag which is provided with the usual hem at the top, and drawing-strings, by means of which it may be closed. Near the upper edge, at one side, is a flap or pocket, B, which is secured to the inside of the bag in such manner that it may be brought over the edge opposite to that to which it is attached, when required, as shown in Figs. 3 and 4 of the drawings.

The bag may be constructed of a single piece of fabric, which is chemically or otherwise prepared so as to retain the moisture of the contents when packed, but it is preferably made of two thicknesses of material, or, in other words, in the form of a double bag, or an external bag and an internal lining, the internal bag or lining being chemically or otherwise prepared to retain the moisture of the inclosed article. Within the flap or pocket is secured a concealed string, D, one end of which projects slightly through a suitable aperture, for the purpose hereinafter explained.

In the modification shown in Fig. 4 a hook, E, is employed in connection with the flap or pocket instead of the string D.

To pack the bag, the flap or pocket is drawn out in the position shown in Fig. 3, and the tobacco or other article is forced in in the usual manner, the flap or pocket containing the concealed string keeping the said string out of the way and in position ready for use subsequently. When properly filled, the flap is folded over the tobacco inside of the bag and the draw-strings drawn so as to close the bag, the bag serving as a seal to prevent the escape of moisture and any possible waste of tobacco. The draw-strings are then tied and the package is ready for the market.

When required for use, the strings are untied and the bag opened in the usual manner, and after a sufficient quantity of tobacco is removed for immediate use the flap is brought over the edge of the bag to the outside thereof, as shown in Figs. 2 and 4, and the flap secured. This may be done by drawing out the concealed string D and tying it around the bag, as shown in Fig. 2, or by means of the hook E, as shown in Fig. 4 of the drawings. As the tobacco is used from time to time the flap is drawn down and the empty portion drawn down over the unemptied portion and secured as before.

Having thus described my invention, what I claim, and desire to secure by Letters Patent, is—

1. The combination, with a tobacco-bag, of a flap secured to the mouth at one side and a fastening device secured to said flap, the flap serving as a seal to the original package and

in connection with the fastening device to secure the bag while in use, substantially as specified.

2. A bag for tobacco or other material, having a flap near the edge on one side, the said flap containing a concealed string, which may be drawn out and tied around the bag to secure it, substantially as specified.

In testimony whereof I affix my signature in presence of two witnesses.

WILLIAM J. CUSSEN.
